UNITED STATES PATENT OFFICE.

CHARLES W. KIRSCH, OF STURGIS, MICHIGAN, ASSIGNOR TO KIRSCH MANUFACTURING COMPANY, OF STURGIS, MICHIGAN, A CORPORATION OF MICHIGAN.

FIXTURE MOUNTING FOR METAL WINDOW CASINGS.

Application filed September 28, 1925. Serial No. 59,014.

This invention has for its object to provide window fixtures such as window-shade roller brackets, curtain rod brackets and other devices used in conjunction with draperies and window-shades, which are easily and quickly attachable to metal window frames without requiring the use of toggle or expansion bolts, or the tapping of perforations in the window frame for the reception and engagement of the shanks of machine screws for securing such fixtures or devices, and further, to provide means whereby the said fixtures or devices are permanently rigidly secured in place.

15 A further object of the invention is to provide fastening devices for securing such devices or fixtures to metal window frames and the like without necessitating the tapping of perforations, to thereby permit fixtures adapted for mounting on wood window-casings and the like to be also mounted on metal frames or casings.

20 In the accompanying drawings illustrating fixtures and fastening devices therefor, respectively, embodying the invention:

Fig. 1 is a fragmentary perspective view of a metal window-casing equipped with a curtain rod bracket provided with integral fastening devices constructed in accordance 30 with the invention.

Fig. 2 is a fragmentary detail section on the line 2—2 of Fig. 1.

Fig. 3 is a fragmentary perspective view of a tool designed for effecting the attachment of devices embodying my invention, to the metal casings.

40 Fig. 4 is a view similar to Fig. 2, showing the curtain rod bracket disposed in the position which it is to occupy on the window casing, and the tool of Fig. 3 disposed in initial position preparatory to effecting the permanent attachment of the bracket to the casing.

Figs. 5 and 6 are perspective views of curtain rod brackets provided with integral fastening devices constructed in accordance 45 with the invention.

Fig. 7 is a fragmentary front elevation of a metal window-casing or the like, equipped 50 with a curtain bracket of the type adapted for mounting on wood-casings, and a device constructed in accordance with the invention

for permanently securing the same to the metal casing.

Fig. 8 is a section on the line 8—8 of 55 Fig. 7.

Fig. 9 is a section on the line 9—9 of Fig. 7.

Fig. 10 is a fragmentary detail perspective view of a metal window-casing equipped 60 with a window-shade roller fixture secured thereto by means of a fastening device constructed in accordance with the invention.

Fig. 11 is a section on the line 11—11 of Fig. 10.

Fig. 12 is a perspective view of the fastening device per se.

Fig. 13 is a fragmentary view in elevation of a metal window-casing equipped with a widow-shade roller fixture secured thereto 70 by means of a fastening device embodying my invention.

Fig. 14 is a section on the line 14—14 of Fig. 13.

Fig. 15 is a perspective view of the fastening device per se.

Heretofore, fixtures have been secured to metal window and door-casings by either boring and tapping perforations in the latter to receive and engage machine-screws passing through perforations in the fixtures, or by boring perforations in the casing and inserting toggle-bolts or expansion bolts. The first-mentioned method is both slow and inefficient, because of the thinness of the metal of which the casing is composed, and the second method is also slow and more expensive and produces a clumsy-looking effect.

My invention comprehends the provision of means integral with the fixture or embodied in a separate device which is both cheap and very neat in appearance, a characteristic common to both embodiments being that the attachment of the fixture is very quickly and easily effected and is both 85 rigid and permanent.

All such fixtures include base or wall-plates, the latter being indicated at Figs. 1 to 6 inclusive; by reference numeral 2 in Figs. 7 to 9, inclusive; by reference numeral 3 in Figs. 10 to 12 inclusive, and by reference numeral 4 in Figs. 13 to 15 inclusive.

The fixtures illustrated in Figs. 7 to 15 inclusive, the base or wall-plates 2, 3 and 4,

respectively, are of the type adapted for mounting on wood-casings and to this end are provided with perforations 5 for the passage of shanks of screws or other fastening devices.

The invention consists in providing bendable projections for passage through perforations in the metal casing and bending over the free end portions of said projections to engage the inner face of the wall of the casing in which the perforations are provided, this operation being generally termed "clinching" and the said projections being, therefore, hereinafter termed "clinchable". The invention further comprehends a certain degree of flexibility or elasticity in the fastening device which materially aids in so attaching the fixture as to always cause the base or wall-plate thereof to bear so firmly upon the casing as to prevent all relative movement between the latter and the fixture under the severest strains or stresses to which the fixtures are usually subjected.

The clinchable projections 6 of Figs. 1 to 6 inclusive are integral with the base or wall-plates 1 of the curtain rod brackets there illustrated. Each thereof comprises a tongue having a bowed portion 7 of substantially semi-cylindrical contour extending from an edge of the plate 1 outwardly, beyond the plane of the outer face of said plate, the portion of said tongue which is adapted to pass through the perforation of the casing being offset from the end of the plate 1 and extending perpendicularly thereto and beyond the plane of the rear face thereof. The projections are in pairs extending from opposite edges of the plate and diametrically of the same.

The perforations 8 in the wall of the casing to which the fixtures are to be secured are preferably round and of far larger diameter than the width of the projections 6. They are relatively so positioned that the distance between their centers is greater than the distance separating the free end portions of the projections and so that when the latter are passed through the said perforations their opposing faces will contact with the walls of the respective perforations least removed from each other. Thus, the greater portion of the area of each perforation will be exposed to view and the access of the projection 9 of the tool for effecting bending or clinching of the projections.

The said tool comprises a suitable body portion 10 for engagement in the hand of the operator and a substantially V-shaped end portion which includes the projection 9 extending substantially perpendicularly to the arm 11 thereof, the latter and the projection 9 extending at angles of about forty-five degrees to the axis of the body portion 10. The elbow-portion constituting the junction of the arm 11 with the projection

9 is preferably arcuate and of small radius. The inner face of this substantially V-shaped terminal of the tool is preferably flat and the outer face convex, so that in cross-section the projection 9 and arm 10 are substantially semi-cylindrical.

In use the projection 9 is inserted into the perforation 8 with its flat face opposed to the projection 6, the size of the latter being such that the outer or convex face of the projection contacts with the wall of the perforation diametrically opposed to the projection when the inner face of the projection 9 contacts with said projection 6. The tool is now turned on the inner arcuate face of the V-recess of the arm 11 and projection 9 as a fulcrum through an arc of about ninety degrees, thus bending the projection 6 to extend parallel with the plate 1 and in snug contact with the inner face of the wall of the casing, the bow-portion 7 of the projection 6 being slightly flexed during this operation and remaining so. Upon then repeating the above operation with respect to the companion projection 6, the plate 1 is very rigidly secured to the casing and is held in very firm and unyielding contact therewith, due to the flexion and spring-like action of the bow-portions 7.

Where the type of fixture adapted for attachment to wood-casings is to be used, the attachment to the metal casing is effected by means of elastic sheet-metal plates, each provided with a pair of diametrically opposed clinchable projections. These plates are of various designs adapted for the several types of fixtures.

Thus, in Figs. 7 to 9 inclusive, the sheet-metal plate 12 is provided with a central oblong slot 13 and clinchable projections 14 at its upper and lower edges midway between its side edges, the pin or hook 15 of the wall-plate 2 being adapted to project through the said slot 13. The plate 2 is provided with a perforation at each side of the pin or hook 15 and the plate 12 is provided with a corresponding spaced pair of indentations 16 which provide conical projections to engage in said perforations and thus accurately position the plate 12 with respect to the plate 2. The plate 12 is somewhat longer than the plate 2, so that its extreme end portions may flex as the projections 14 are clinched to produce the spring-like effect above mentioned to hold the plate 2 in very firm contact with the casing. The plate 12 is very slightly bowed throughout its length by the clinching operation and the conical projections thus so firmly engaged in the perforations of the plate 2 as to obviate all possibility of disengagement, except by the use of excessive force.

The plate 16 shown in Figs. 10 to 12 inclusive is adapted for securing the conventional window-shade roller bracket 17 of

Figs. 10 and 11, the base or wall-plate 3 of which comprises a flange of the bracket element and is provided with two perforations in which the conical projections formed by the indentations 18 engage. The plate 16 is longer than the plate 3 and upon clinching its end projections 19 will be slightly flexed, for purposes aforesaid.

In Figs. 13 and 14, I have illustrated the conventional type of window-shade roller adapted to be mounted on opposed side faces of the window casing and which includes the plate 4 provided with perforations for the passage of fastening devices and the central dished portion 20 which is slotted or perforated to receive an end element of a shade-roller, this dished portion being circular. The plate 21 provided with clinchable projections 22 and indentations 23 to engage in the perforations of the plate 4, is provided with a central, circular opening 25 through which the dished portion 20 is adapted to project, the plate 21 being somewhat longer than the plate 4, so that upon clinching the projections 22 it will be slightly flexed as and for the purposes aforesaid.

From the foregoing it will be obvious that any kind of a fixture may be easily and rigidly secured to a metal casing or trim by means of a plate designed to adapt it for co-operation with the perforations of the fixture ordinarily used for the passage of fastening devices or by providing the wall-plate or plates of the fixture with the integral clinchable projections shown in Figs. 1 to 6 inclusive.

In so far as the tool above described constitutes a part of the invention, the latter may be expressed as constituting a method as defined in appended claims.

I claim as my invention:

1. Means for securing conventional fixtures of the type specified to metal window-casings and the like comprising a flexible elastic plate provided with clinchable projections for passage through perforations and bending to engage the inner face of a perforated wall, said plate including formations for engagement with the fixture to maintain the latter in fixed position relatively to said perforations through which the projections pass.

2. Means for securing conventional fixtures of the type specified to metal casings and the like, said means comprising a plate equipped with clinchable projections adapted to pass through perforations in the casing and be bent over to engage the inner surface of the perforated wall thereof for holding said plate in a fixed position relatively to said casing, said plate including formations adapted to engage the fixture for retaining the latter in fixed position relatively to said plate, the said plate being elastic and flexed

by bending of said projections to exert yielding pressure on the fixture.

3. Means for securing conventional fixtures of the kinds specified to metal casings and the like, said fixtures having perforations, said means comprising a plate having clinchable projections for passage through perforations in the casing and adapted to be bent over to engage the inner face of the perforated wall of the casing, and formations on said plate for engaging in the perforations of the fixture to retain the latter in fixed position relatively to the plate, said plate being elastic and the perforated portion of the fixture disposed between the same and the perforated wall of the casing, said plate being flexed by the bending of the projections to thereby exert a yielding clamping pressure on the fixture.

4. A fixture of the type specified including a member having a perforated wall-plate and a member constituting a fastening device, the latter comprising a plate equipped with clinchable projections for passage through perforations in a wall of a metallic window-casing or the like and to be bent over to engage the inner face of said wall, said plate provided with projections for engaging in the perforations of said wall-plate when the latter is disposed between said last-named member and the casing.

5. A window-fixture or the like comprising two members, one thereof including a wall-plate for contact with a face of the casing and the other thereof constituting a clamping member, the latter comprising a plate equipped with clinchable projections for passage through perforations in the casing and adapted to be bent to engage the inner surface of the perforated wall of the latter, said plate disposed outwardly of the wall-plate of said first-named member, and inter-engaging formations on said plate and said wall-plate for holding the latter in fixed position relatively to said plate when the latter is secured to the casing.

6. A window-fixture or the like comprising two members, one thereof including a wall-plate for contact with a face of the casing and the other thereof constituting a clamping member, the latter comprising an elastic plate of greater length than said wall-plate and equipped at its ends with clinchable projections for passage through perforations in a wall of a metal window-casing and adapted to be bent over to engage the inner face of the said wall, said plate adapted to be flexed by the bending of said projections to thereby exert a yielding pressure on the wall-plate, the latter disposed between said plate and the wall of the casing.

7. A window-fixture or the like comprising two members, one thereof including a wall-plate for contact with a face of the casing and the other thereof constituting a

clamping member, the latter comprising an elastic plate of greater length than said wall-plate and equipped at its ends with clinchable projections for passage through perforations in a wall of a metal window-casing and adapted to be bent over to engage the inner face of the said wall, said plate adapted to be flexed by the bending of said projections to thereby exert a yielding pressure on the wall-plate, the latter disposed between said plate and the wall of the casing, said plate and said wall-plate having inter-engaging formations for retaining the same in fixed position relatively to each other.

8. The method of securing fixtures of the type specified to metallic window-casings, which consists in perforating the window-casing, associating with the fixture clinchable projections for passage through perforations in the casing, interposing elastic means between said projections and the fixture, passing said projections through perforations in the casing, and then bending the same while maintaining the elastic means flexed to cause the said projections to engage the inner face of the perforated wall of the casing and maintain said elastic means permanently flexed. 20 25

CHARLES W. KIRSCH.
